DESK

John A. Gale, 978 E. Shady Lane, Wayzata, Minn.

Filed May 25, 1964, Ser. No. 80,135

Term of patent 14 years

(Cl. D33—7)

FIG. 1 is a rear side perspective view of a desk embodying my novel design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a sectional view taken substantially along line 7—7 of FIG. 1 looking in the direction of the arrows.

I claim:

The ornamental design for a desk, as shown.
